UNITED STATES PATENT OFFICE.

WALTER UDESEN, OF PORT ARTHUR, ONTARIO, CANADA.

HAT-FASTENER.

1,361,204.

Specification of Letters Patent.

Patented Dec. 7, 1920.

Application filed October 13, 1919, Serial No. 330,203. Renewed October 25, 1920. Serial No. 419,491.

To all whom it may concern:

Be it known that I, WALTER UDESEN, a citizen of the Dominion of Canada, residing at Port Arthur, in the Province of Ontario, 5 Dominion of Canada, have invented new and useful Improvements in Hat-Fasteners, of which the following is a specification.

The object of my present sole invention is to provide a hat fastener that is susceptible 10 of ready application and removal, and is highly efficient for the purpose that its name imports.

To the attainment of the foregoing, the invention consists in the peculiar and ad- 15 vantageous hat fastener as hereinafter described and definitely claimed.

In the accompanying drawings, hereby made a part hereof:

Figure 1 is a side elevation showing my 20 novel fastener as the same appears when ready for use.

Fig. 2 is a similar view of the fastener with the point member displaced and the springs extended to secure the fastener in 25 the hair of the wearer of the hat; a portion of the adjacent wall of the hat body being shown in section.

Fig. 3 is a plan view of the complete device, or a view taken at right angles to 30 Fig. 1.

Fig. 4 is a detail section showing the connection of the springs to the plunger and the arrangement of the plunger and springs in the tubular body of the fastener.

Fig. 5 is a detail view of the point member *per se* of the device.

Similar numerals of reference designate corresponding parts in all of the views of the drawings.

Among other elements my novel hat fastener comprises a tubular body 1.

Movable rectilinearly in the body 1 is a plunger rod 2 having at its outer end a head 3.

Connected to the forward end of the plunger rod 2 and adapted to be sheathed in the tubular body 1, are spring-retainers 4, the function of which is to rest in the hair of the hat wearer and thereby prevent 45 displacement of the hat. This capacity of the retainers 4 will be readily appreciated when it is stated that when extended from the forward end of the tubular body 1, the retainers will assume the position illustrated 50 in Fig. 2.—*i. e.*, will extend in curvilinear

manner and radially from the inner end of the tubular body 1.

Fixed with respect to the tubular body 1 at an intermediate point in the length thereof is a combined finger-piece and stop 60 5 that is adapted to bring up against the outer side of a side wall of the hat body.

Arranged at opposite sides of the tubular body 1 and the plunger rod 2, and connected to said tubular body and plunger 65 rod are lazy-tong members 6.

At 7 is the point member of the device; the said point member having a shank 8 which is designed to be removably sheathed in the forward end of the tubular body 1. 70

In the practical use of the fastener, the shank member of the point member 7 is ar- 75 ranged in the forward end of the tubular body 1, while the other parts are relatively arranged as shown in Fig. 1. The point

member 7 is then forced through the wall 9 of a lady's hat, so as to carry the tubular body 1 through said wall. The plunger rod 2 is then forced forwardly in order to dis- 80

place the point member 7, which point mem- 85 ber is then recovered by the user for subse- quent use. The plunger rod 2 is then re- tracted and the hat is positioned upon the head of the wearer, and thereupon the plunger rod 2 is forced forwardly so as to spread the retaining springs 4 in the hair 90 of the wearer, with the result that the fas- tener will be strongly secured to the hair, and hence will serve efficiently in fastening the hat upon the head.

By reference to Fig. 2, it will be apparent that by exerting with the thumb and fore- finger inward pressure upon the outermost portions of the comparatively long interme- 95

diate lazytong members 6, which outermost portions are preferably equipped with anti- friction rolls 10 to afford bearing surfaces for the thumb and fore-finger, the user is enabled to expeditiously and easily retract the plunger rod 2, and thereby withdraw 100

the spring retainers 4 from the hair and sheath the same in the tubular body 1. From 105 this it follows that the lazytong members constitute a compressible handle for the easy withdrawal of the retainers 4 without distortion of the hat or disarrangement of the hair of the wearer. Then if desired, the tubular body 1 may be withdrawn from the wall of the hat body and the shank of the point member 7 may be sheathed be- 110

tween the spring-retainers 4 and in the forward portion of the tubular body 1 for subsequent use of the device.

While I prefer to employ the point member 7 in combination with the tubular body 1 for the purpose indicated, I do not desire to be understood as confining myself to the employment of the point member 7, inasmuch as any extraneous device may be employed to puncture the side wall of the hat body as a condition precedent to the introduction into said wall of the tubular body 1.

Having described my invention, what I claim and desire to secure by Letters-
15 Patent, is:

A hat fastener comprising a tubular body having a combined stop and finger-piece at

an intermediate point in its length, a plunger rod movable rectilinearly in said tubular body, retaining spring strips connected 20 to the forward portion of the plunger rod and adapted upon forward movement of said rod to extend radially in curvilinear manner from the forward end of the tubular body and upon retraction of the rod to be 25 sheathed in the tubular body and lazytong members connected to and extending laterally from the tubular body and the plunger rod; the intermediate lazytong members being comparatively long and constituting a 30 compressible handle.

In testimony whereof I affix my signature.

WALTER UDESEN.
